POST BINDER MECHANISM

John Schade, Holyoke, Mass., assignor to National Blank Book Company, Holyoke, Mass., a corporation of Massachusetts

Application April 15, 1946, Serial No. 662,252

3 Claims. (Cl. 129—4)

1

This invention relates to improvements in post binders of the same general type, as that shown by prior patent to Schade No. 2,211,517 of 1940 and other granted patents, such as Patent No. 2,125,048 of 1938 to G. E. Hamlin.

The purpose is to provide a better latch mechanism for binding and releasing the posts in the binder. The improved binder is better from the user's standpoint in that it is more convenient to use, is not so likely to get out of order, and it will last longer without repair or replacement of parts. While it may cost a little more for the maker, this can not be anywhere near enough to offset the goodwill he will get by furnishing the user with a better operating structure to last longer than the prior art binder.

The improvement consists in the detail relation of parts making the new combination. An example of the combination and the detail relation to make it, is given by the drawings and the description.

Fig. 1 is a back view of the binder assembly with the cover of the top binder tube cut away to show the parts of the mechanism;

Fig. 2 is taken on line 2—2 of Fig. 1 to show a top view of the mechanism in the binder tube;

Fig. 3 is a view on line 3—3 of Fig. 1 to show the binder tube and latch releasing slide in cross section;

Fig. 4 is a perspective view of the releasing slide;

Fig. 5 is a fragmentary detail view showing a latch plate cammed in post-releasing position; and

Fig. 6 is a fragmentary end view to show a modified form of a post releasing actuator means.

As shown in Fig. 1 a pack of loose leaf sheets 1 is threaded on posts 2 between the lower binder tube or bar 3 and upper binder tube 4. These function as holding strips or bars. As shown in Fig. 3, they are made by turning a flat metal strip into a flattened tube form.

Posts 2 are suitably secured to binder tube 3 by rivets or otherwise as desired. Tube 4 is provided with holes 6 to receive the posts 2. This tube is releasably secured to the posts by post-latching mechanism to be described.

A latch release slide 7 shown in perspective by Fig. 4, and in cross section by Fig. 3 as it lies inside tube 4, is a shallow U-shaped metal strip with the longitudinal portion 8 of inverted U-shape to form narrow channeled portions 9 on each side for the bearing surfaces to slide in binder tube 4. Slide 7 is positioned in tube 4 (Figs. 1 and 3) and is slidable in this tube 4 between a post-latching and post-releasing position.

A latch plate 10 with a post hole 11, Figs. 1, 2 and 5, has a narrowed portion 12 with two prongs 13, Fig. 2, by which plate 10 is pivoted on a frame

2

15, for latching and releasing position with relation to its post 2. The prongs 13 are located in notches 14, Fig. 1, of the U-shaped pivot frame 15. The frame 15 is seated in the bottom of tube 4 and fixed thereto by suitable means. Since the height of the upright arms of frame 15 are slightly less than the inside dimension of the binder tube, I prefer to punch a slot in the base of the frame 15 so that when the frame is placed in position, the metal surface of tube 4 may be depressed or bumped in as at point 15 into the slot thereby holding the frame against longitudinal movement in the tube. The frames, however, may be fastened in place to tube 4, if preferred, by retaining screws. As mentioned, the arms of frame 15 are of approximately the same height as the interior of tube 4. Therefore, the prongs 13 are held in notches 14 by the undersurface of tube 4, Figs. 1 and 5.

20 Latch plate 10 is normally held in a canted post-latching position, as shown in Fig. 1. The mechanism for doing this is best shown in the enlarged view of Fig. 5, the plate 10 in that view being in post releasing position. A spring 16 is fastened on frame 15 by an anchor stud 17 on the base of the frame 15, and by a hook 18 of metal cut and bent from the narrowed portion of plate 10 adjacent its hole 11. The spring 16 tends to pull the plate 10 downwardly canting the plate on its pivot in frame 15 as described.

25 A latching assembly as described is provided for each post 2 and, as shown in Figs. 1 and 2, each such assembly is located on the corresponding side of each post hole so that as the latch release slide 7 is moved to the right (see Figs. 1 and 2), the slide will cause both plates 10 to be cammed into post releasing position simultaneously in a way to be described.

30 It will be noted in Fig. 4 that openings 19 and 20 provided in slide 7 straddle the latching units. Cam portions 21 alongside these openings move with slide 7, and when moved with the slide to the right from the position in Fig. 1, cam the latch plate 10 out of engagement with the posts.

35 Cam portions 21 are formed from metal of slide 7, Fig. 4. They are bent upwardly from the two openings 19 and 20. The openings are positioned in slide 7 below the latching assembly. As shown, cam portions 21 stand vertically to form

40 inclined planes on which a latch plate 10 may ride. In this construction I have turned the slanting edges of the cams 21, as at 22, to a 90° angle with the plane of the vertical portions. In this way I have provided a smooth metal sur-

45 face on which the latch plate 10 may ride. There is less frictional resistance. Portions 23 are turned up from the metal of slide 7 at openings 19 and 20 to serve as guides for maintaining the slide 7 in proper alignment to each frame 15 for 50 relative sliding movement.

Slide 7 is normally urged to permit plates 10 to grip posts 2, as in Fig. 1. The slide is urged, as stated, by spring 24 fastened between a hook 25 punched from the metal of slide 7 and the anchor 17 of frame 15. A notch 26 is cut in the inner edge of opening 19 to accommodate the hook 17. Outward movement of slide 7 under tension of spring 24 is to the left in Fig. 1, and is limited by the inner edge of opening 19 striking against the edge of frame 15. On the end of slide 7 an actuator 27 extends from the open end of tube 4.

To operate slide 7 to post release position, to cam the plates 10 out of canted position with respect to the posts, finger pressure on the actuator 27 is exerted inwardly of tube 4. The tube 4 may be lifted off the posts when plates 10 are put out of their canted positions by cam portions 21. Actuator 27 is formed by turning over the metal of slide 7 or by providing any suitable cap therefor which may be pushed into the end of tube 4 against the spring action of spring 24.

A modified form of the post releasing device is shown in Fig. 6. In this form both ends of tube 4 are capped, the same as the one shown. An actuating button 28 in a slot 29 cut in the top of tube 4 is fixed to a slide lever 30 on slide 7 for moving the latter to post release position against the action of spring 24.

By making the construction of parts for a post binding mechanism as described above, a post binder of superior lasting qualities is provided. The binder will endure hard usage without causing malfunction and failure of parts. The simplicity in construction and ease in operation of the latching and releasing elements make a smoothly functioning article which will stand up longer in use and give more satisfactory service than any prior devices, now known to me.

Having disclosed my invention, I claim:

1. In a post binder of the type having posts, a bottom bar holding the posts, a removable top tube with cross holes to receive the posts, and latch mechanism in the tube to latch it on the posts, the combination of a flattened top tube, a sheet metal slide with a multiple open channel section arranged with a central inverted U-shape channel portion and narrow U-shape portions on each side, the latter portions fitting the bottom and sides of the tube for longitudinal guided sliding movement without much friction, said slide having substantial openings for the posts in the sliding relation, bent vertical portions of the slide formed with slanting cam edges in the longitudinal relation to the tube and adjacent the side edges of said openings, means including a spring to hold said slide in one position of adjustment with relation to said posts, a latch plate for each post, means to pivot the latch plate for movement to horizontal and canted positions with relation to the post, such latch plate having a post hole with edges adapted to bind on the post in canted, and free the post in horizontal position, a spring for each plate to urge it to canted position to hold said cam edges near said plates when in canted position, and a finger actuated piece to move the slide to a second position of adjustment relative to said posts against its spring means to move the cam edges against said plates and the latter to horizontal position against their springs.

2. In a post binder of the type described the combination of a top tube, a shallow channel sec-

tion sheet metal slide fitting transversely in the bottom of the tube for most of its length and adapted for finger actuation, said slide having a reverse channel section bent up from its lower side, a substantial opening adjacent each end of the slide, vertical inclined cam portions struck up from the metal of said reverse channeled portion and arranged longitudinally at the edges of said opening, pivot supporting means adjacent said openings, a latch plate for each opening pivoted on said means, a spring for each plate urging it out of horizontal position into canting and latching position with relation to a post, said inclined cam portions adapted upon the movement of said slide to move the latch plates to horizontal and unlatching positions with relation to their posts, spring means normally holding the parts in latching position, said slide and parts adapted to move the plates to unlatching positions upon finger actuation of said slide.

3. In a post binder of the type described the combination of a top tube having one of its ends open, a shallow multiple channel section sheet metal slide with a reverse U-shape channel section bent up from its lower side leaving relatively narrow channels adjacent each of its upright sides, said slide fitting longitudinally in said tube for most of its length, a finger actuated piece attached to each slide and extending from said open end of the tube for moving said slide inwardly of the tube on said narrow channeled portions from one position of adjustment in the tube to a second position, said reverse channel section being cut away to provide openings for registration of a post in said openings in either position of adjustment, vertical inclined cam portions struck up from the metal of the reverse channeled portion adjacent the edges of said openings and arranged longitudinally in the tube, a pivot supporting means fixed in said tube and arranged in said openings adjacent each said post a latch plate pivoted on each said means, a spring attached to each said plate and said means to urge the plates to canted position with relation to said posts and grip the posts against removal of said tube, a spring means attached to said slide and the adjacent pivot supporting means such spring normally urging said slide outwardly of said tube open end, said adjacent pivot supporting means holding the slide against further outward movement by contact with the inner edge of its adjacent slide opening whereby the slide and latch plate are normally in the first position of adjustment in post latching relation, said slide upon inward pressure of said finger piece being adapted for moving said inclined cam portions to pivot the latch plates to horizontal position with relation to said posts whereby the posts may be freed of the plates and said top tube may be removed from the posts.

JOHN SCHADE.
